INVENTOR
Charles H. Thomas,
by
Arthur Perkins,
ATTORNEY

UNITED STATES PATENT OFFICE

CHARLES H. THOMAS, OF NEW BRITAIN, CONNECTICUT, ASSIGNOR TO THE AMERICAN HARDWARE CORPORATION, OF NEW BRITAIN, CONNECTICUT, A CORPORATION OF CONNECTICUT

PADLOCK

Application filed October 15, 1929. Serial No. 399,761.

My invention relates to the class of locks above named, and an object of my invention, among others, is the simple construction of a lock of this type that shall be provided with means to prevent opening without the use of a key.

One form of a lock embodying my invention and in the construction and use of which the objects herein set out, as well as others, may be attained is illustrated in the accompanying drawings, in which—

Figure 1 is a side view of a lock embodying my invention.

Figure 2 is a view in central lengthwise section on a plane passing through the center of the branches of the yoke, the parts being in position when unlocked.

Figure 3 is a view partially in section on the same plane but showing the parts just at the time of engagement of the yoke with the locking bolt in the closing movement of the yoke or shackle.

Figure 4 is an end view of the lock.

Figure 5 is a side view with parts broken away to show construction, the parts being in a locked position.

Figure 6 is a view in section on a plane denoted by the dotted line 6—6 of Figure 2.

Figure 7 is a detail view in section on a plane denoted by the dotted line 7—7 of Figure 5.

Figure 8 is an isometric view illustrating the shape of the locking bolt.

Figure 9 is a similar view but looking at the opposite side of said bolt.

In the accompanying drawings the numeral 10 denotes the case of my improved lock, that may be of the shape of locks generally of this type, said case having a well 40 for the long arm 11 of a shackle that is seated upon a spring 12 in the bottom of said well. The case has a key plug 13 of ordinary construction which contains tumblers cooperating with tumblers 14 located in the case and operating in a manner common to locks of this type. The short arm 15 of the shackle has a notch for engagement by the nose of a locking bolt 16.

All the parts thus far described, except as 50 to the locking bolt, are of old and well known

construction and further and detailed description are therefore omitted herein.

The locking bolt 16 has a locking recess 17 in its under surface into which a locking stud 18 projects from the plug 13, this recess being of such size that the stud prevents backward movement of the bolt and retains it in its locked position. A releasing recess 19 opens from the locking recess, this releasing recess being deeper on one side than on the other, as shown in Figure 7 of the drawings, thereby presenting a locking shoulder 20 abutting the stud 18 when the parts are in their locked positions and therefore preventing backward or unlocking movement of the 60 unlocking bolt, and which unlocking movement can be accomplished only by rotating the key plug 13 by use of a key in the ordinary manner.

It will thus be seen that when the parts 70 are in their locked positions the locking bolt 16 can be released from the shackle only by the use of a key, and it will therefore be impossible to surreptitiously unlock the mechanism as by means of blows delivered upon the lock case, which operation has heretofore been found to be successful in the hands of a skillful manipulator.

In order to permit free backward movement of the locking bolt and thereby permit 80 the parts to be automatically locked when the shackle is pushed inwardly, the nose of the bolt is formed with a releasing cam 21 on its end adapted to receive a cam 22 on the end of the short arm 15 of the shackle. When 85 the parts are in the position shown in Figure 2 and it is desired to lock the mechanism the shackle is pushed inwardly and the engagement of the cams 21 and 22 will cause the bolt 16 to be rocked out of the position shown in Figure 7 and to the position shown in Figure 3, in which position the stud 18 lies entirely below the locking shoulder 20, and the bolt 16 may therefore freely move backward to permit full movement of the shackle inwardly. 90 When the latter has reached its inward position the spring 23 will force the bolt to its closed position, and the engagement of the flat side of the notch in the arm 15 with the flat side of the nose of the bolt will cause the latter 95 100

to be rotated into the position shown in Figure 7, in which position backward movement of the bolt 16 can be attained only by the use of a key.

- 5 In accordance with the provisions of the patent statutes, I have described the principles of operation of my invention, together with the device which I now consider to represent the best embodiment thereof; but I desire 10 to have it understood that the device shown is only illustrative, and that the invention may be carried out by other means and applied to uses other than those above set out.

I claim—

- 15 1. A padlock including a case, a shackle movably mounted within the case, a locking bolt rotatably mounted in the case and longitudinally movable for engagement with said shackle, said bolt having a recess cut away on 20 one side, a key plug movably mounted in the case, and a stud projecting from said key plug into said recess to prevent backward movement of the locking bolt independently of the plug in one position of said bolt but to permit 25 such movement when the cut away portion of the recess is opposite said stud.

2. A padlock including a case, a shackle movably mounted within the case, a locking bolt rotatably mounted in the case and longitudinally movable for engagement with said shackle, said bolt having a recess forming a shoulder, a key plug rotatably mounted in 30 said case, a stud projecting from said plug into said recess, and means for rotating said bolt to pass said shoulder from a position opposite said stud.

3. A padlock including a case, a shackle movably mounted within the case, a locking bolt rotatably mounted in the case and longitudinally movable for engagement with said shackle, said bolt having a recess forming a shoulder, a plug movably mounted in the case, a stud projecting from said plug, and means on the shackle and bolt for rotating the latter 45 to remove said shoulder from a position opposite said stud.

4. A padlock including a case, a shackle movably mounted in the case and having a recess with a flat side, a locking bolt rotatably mounted in the case and longitudinally movable for engagement with said shackle, said bolt having a nose with a flat side to engage the flat side of said recess, a key plug movably mounted in the case, a stud projecting from 55 said plug into a recess with a shoulder in said locking bolt, and means for rotating said bolt to locate said shoulder in a position to permit longitudinal movement of said bolt without interference by said stud.

5. A padlock including a case, a shackle movably mounted within the case and having a cam surface on one end thereof, a locking bolt rotatably mounted in the case and longitudinally movable for engagement with said shackle, said bolt having a cam surface to

engage that on the shackle to effect rotating movement of the bolt, said bolt having a recess with a shoulder on one side, a key plug movably mounted in the case, and a stud projecting from said plug into said recess for engagement with the side thereof when the bolt is in one position, but for disengagement therefrom when the bolt is rotated by the action of said cam surfaces.
